CLAIM

The ornamental design for the personal soccer ball fan, as shown and described.

DESCRIPTION

FIG. 1 is a perspective view of the personal soccer ball fan showing my new design;

FIG. 2 is a side elevational view of the personal soccer ball fan;

FIG. 3 is an opposite side elevational view thereof;

FIG. 4 is a rear elevational view thereof;

FIG. 5 is a front elevational view thereof; and,

FIG. 6 is a top plan view of the personal soccer ball fan, the bottom being a mirror image of that shown.
